United States Patent Office

Des. 181,645
Patented Dec. 10, 1957

181,645

BEVERAGE DISPENSER

John T. Harris, Burlington, N. J., assignor to Rudd-Melikian, Inc., Hatboro, Pa., a corporation of Pennsylvania

Application May 9, 1956, Serial No. 41,416

Term of patent 14 years

(Cl. D2—3)

Fig. 1.

Fig. 2.

Fig. 1 is a perspective view of the front and one side of a beverage dispenser, showing my new design, the opposite side and back being plain as indicated in Fig. 2.

Fig. 2 is a plan view of the beverage dispenser shown in Fig. 1.

I claim:

The design for a beverage dispenser, as shown.
